ADJUSTABLE HOLDER FOR LIPSTICKS AND
THE LIKE

Howard F. Reichenbach, Waterbury, Conn., assignor to The Chase Companies, Incorporated, Waterbury, Conn., a corporation of Connecticut

Application May 1, 1936, Serial No. 77,341

3 Claims. (Cl. 206—56)

This invention relates to an improvement in adjustable holders for lipsticks, shaving soap, etc., etc.

One of the main objects of the present invention is to provide a simple, attractive and durable adjustable holder suitable for use in connection with lipsticks, etc.

A further object of the present invention is to provide a low-cost adjustable holder which 10 may be assembled with superior facility and convenience.

With the above and other objects in view, as will appear to those skilled in the art from the following, considered in conjunction with the 15 accompanying drawing and appended claims, the present invention includes all features disclosed therein which are novel over the prior art.

In the accompanying drawing:

Fig. 1 is a view in side elevation of a lipstick 20 holder embodying the present invention;

Fig. 2 is a central longitudinal sectional view taken on the line 2—2 of Fig. 1;

Fig. 3 is a transverse sectional view taken on the line 3—3 of Fig. 1;

Fig. 4 is a view in side elevation of the lipstick 25 holder with the cap removed;

Fig. 5 is a view in side elevation of the cap;

Fig. 6 is a perspective view of the carrier, detached;

Fig. 7 is a perspective view of the operating- 30 button or member; and

Fig. 8 is a sectional view corresponding to Fig. 3, but showing a modified form of structure.

The particular adjustable lipstick holder herein 35 chosen for the illustration of the present invention in Figs. 1 to 7 inclusive, includes a relatively-deep cup-shaped body, generally designated by the numeral 10, and comprising a tubular portion 11 open at one end and having its opposite end closed by an end-wall 12 which may be formed integral with the said tubular portion. At the junction point of the tubular portion 11 with its end-wall 12, the body 10 is provided with an annular rim or bead 13.

Adapted to fit over the body 10 is a relatively-deep cup-shaped cap 14 comprising a tubular portion 15 shaped and sized so as to be readily telescoped over the tubular portion 11 of the body 10, and an end-wall 16 serving when the cap is in place to close the open end of the said body 10.

Mounted within the body 10 with capacity for reciprocating movement therein is a cup-shaped carrier 17 which may be conveniently formed 50 from sheet-metal such as brass, and which in-

cludes a tubular portion 18 and a bottom wall 19. A portion of the bottom-wall 19 of the carrier 17 is pierced and struck up to form a tongue 20 spaced a short distance inwardly from the adjacent side-wall of the carrier. The said tongue 20 is pierced and the metal displaced to provide gripping-means in the form of two opposed inwardly-extending resilient retaining-prongs 21—21. Clasped between the retaining-prongs 21, just referred to, is the shank 22 of an operating-head or button, generally designated by the numeral 23, and including also a head 24. The said head 24 preferably has its outer face curved to substantially conform to the curvature of the outer surface of the tubular portion 11 of the 15 body 10.

The operating-button 23 above described may be conveniently formed from molded material such, for instance, as bakelite, urea formaldehyde, etc., and has the upper edge 25 of its 20 shank 22 tapered to cut into a lipstick or the like which may be pressed thereover and which is retained by its flowage around the said shank.

For the purpose of permitting the operating-button 23, and hence the carrier 17, to be moved 25 longitudinally of the body 10, the tubular portion 11 of the said body is provided with a longitudinal slot 26 of a width sufficient to permit the shank 22 of the said operating-button to freely extend therethrough and closed at its outer end 30 by a stop-web 27 formed by the material of the outer end of the tubular portion 11 of the body. To clear the shank 22 of the operating-button 23 and thus permit its lower edge to substantially engage with the bead 13 of the body 10, the tubular portion 15 of the cap 14 is formed with a 35 clearance-notch 28.

In line with the opening provided between the retaining-prongs 21—21 of the tongue 20, the tubular portion 18 of the carrier 17 is provided 40 with a perforation 29 through which the shank 22 of the operating-button 23 projects for engagement with the retaining-prongs 21—21. The walls of the perforation 29 serve in conjunction with the walls of the opening in the tongue 45 20 from which the prongs 21—21 are deflected, to stabilize the operating-button 23.

In assembling the lipstick holder above described, the carrier 17 is inserted into the body 10 and its perforation 29 brought into alignment 50 with the longitudinal slot 26 in the tubular portion 11 of the said body. The shank 22 of the operating-button 23 is now inserted through the said slot 26 and perforation 29 and forced between the resilient retaining-prongs 21—21 until 55

its oppositely-located stop-shoulders 22^a abut against the periphery of the carrier 17. After insertion, as described, the operating-button 23 is effectively retained in place against all but 5 forcible withdrawal by the action of the retaining-prongs 21-21 which are preferably arranged, as shown particularly well in Fig. 3, so that their sharp edges tend to "bite", so to speak, into the shank 22 when any effort is made to 10 withdraw the operating-button 23. If, during the insertion of the shank 22 of the operating-button 23, as above described, the said shank is slightly canted, so that its upper rear corner, to 15 which its tapered portion 25 extends, is first introduced into the perforation 29 of the carrier 17, the installation will be facilitated.

If desired and as shown in Fig. 8, a finger-button 30 may be substituted for the operating-button 23, before described. This finger-button 20 in question is provided with a circular head 31 having a convex outer face, and with a cylindrical shank 32 formed adjacent its inner end with an annular groove 33, which latter results in the formation of an outwardly-facing retaining-abutment 34. The tongue 20 of the carrier 17 is pierced for the passage through it of the said shank 32, and the metal displaced by piercing the tongue is bent to provide an inwardly-extending retaining-prong 35, which extends into 30 the groove 33 in the shank 32 of the operating-button and engages with the retaining-abutment 34 thereof.

In connection with the assembly of adjustable lipsticks of the general type herein shown, one of 35 the most vexing operations has been to couple the operating-button with the carrier. From the foregoing, it will be seen that by means of the present invention, the installation of the operating-button and its connection to the carrier is 40 rendered so simple that it ceases to be a problem of any import.

The invention may be carried out in other specific ways than those herein set forth without departing from the spirit and essential characteristics of the invention, and the present em- 45

bodiments are therefore to be considered in all respects as illustrative and not restrictive, and all changes coming within the meaning and equivalency range of the appended claims are intended to be embraced therein.

5

I claim:

1. An adjustable holder of the class described including in combination: a hollow body having a slot therein; a cup-shaped carrier located in the said hollow body and having the material of its end-wall struck up to form a tongue spaced inwardly from the side-wall of the carrier, the said tongue being provided with a yielding retaining-prong; and an operating-button having a portion extending through the slot in the said body and through the side-wall of the carrier and into engagement with the yielding retaining-prong of the latter, the said yielding retaining-prong serving to retain the operating-button in 10 assembled relationship.

15

2. An adjustable holder of the class described including in combination: a hollow body having a slot therein; a cup-shaped carrier located in the said hollow body and having the material of its end-wall struck up to form a tongue spaced inwardly from the side-wall of the carrier, the said tongue being provided with a pair of opposed yielding retaining-prongs; and an operating-button having a portion extending through the slot in the said body and through the side-wall of the carrier and into engagement with the pair of opposed yielding retaining-prongs of the latter, the said pair of opposed yielding retaining-prongs serving to retain the operating-button in 20 assembled relationship.

25

3. An adjustable holder of the class described including in combination: a hollow body having a slot therein; a carrier located in said hollow body and provided with yielding button-retaining means; and an operating-button having a portion extending through the slot in the said body and provided with an outwardly-facing retaining-abutment engageable with the button-retaining means of the said carrier.
